[57] ABSTRACT

A crane structure comprising a trolley, a beam member which is suspended from the trolley by flexible cables, a hoist on the trolley for changing the elevation of the beam, and a pair of hook assemblies. The beam is constructed to provide cam portions adjacent bearing seats so that the hook assemblies are guided from one bearing seat to another when the beam is lowered until the weight of the hook assembly is supported by a surface beneath them. A hook assembly stabilizing mechanism is also provided. The disclosure also includes a novel laminated hook construction which establishes line contact with a support which line forms a pivot axis for hook adjustment.

OVERHEAD LOAD SUPPORTING STRUCTURE AND METHOD

BACKGROUND OF THE INVENTION

1. The Field of the Invention

The invention relates to an overhead load supporting structure and more particularly relates to a load supporting structure having load engaging hooks or grabs which are manipulated to engage a load and transport the load from place to place within a building structure or the like.

Overhead load supporting structures such as cranes equipped with load engaging hooks are often utilized in steel mills or similar plants to transport ladles for molten metal. Such ladles are generally constructed with trunions extending from diametrically opposed locations on the ladle. The trunions are engaged by the hooks for transport.

Generally, support structures for transporting ladles of the type referred to include an overhead trolley movable along tracks, a hoist mechanism, and a hanger beam which is suspended by cables from the trolley. Where the load supporting structure is a crane the trolley supporting tracks are movable so that an entire floor area of a building can be serviced by the crane. The cables are suitably trained around sheaves on the hanger beam and trolley so that the hoist mechanism can effect changes in the elevation of the hanger beam with a mechanical advantage. Hook or grab structures depend from the beam and when a ladle is to be transported these hooks are connected to the ladle trunions.

In many instances ladles of different diametrical dimensions are utilized in the same steel mill. Accordingly crane structures of the type referred to must be equipped to transport ladles having various dimensions between the trunions. Since the supporting structures carrying the hooks are commonly rigid in construction, shifting the position of the hook structures relative to the hanger beam to accommodate the variously dimensioned ladles has been a problem.

2. THE PRIOR ART

Proposals have been made for the use of power driven shifting mechanisms for moving the load supporting structures relative to the beam. Such proposed mechanisms are powered by electrical, hydraulic, or pneumatic motors integral with the hanger beam which generally utilize a suitable system of gears, levers, or cables to shift the hooks. The use of such power driven shifters has not been entirely satisfactory due to excessive shock forces which are transmitted to the elements of the drive train from the hooks. Moreover, the drive trains are, during use in ladle transport, subjected to extremely high ambient temperatures. Both the exposure to high temperature and the attendant large variation in ambient temperatures are factors which make the drive train susceptible to failure. Furthermore, flexible hoses or wiring through which power is supplied to the shifting mechanisms have been subjected to fouling during operation of the crane and to deterioration from the intense heat of the environment.

The prior art has also proposed to shift hooks of a crane structure of the type referred to without the use of motors integral with the hanger beams. Such proposals retained the hook shifting mechanism on the hanger beam and employed an auxiliary hoist to operate the

hook shifting mechanism. The auxiliary hoist engaged a lever or cable of the shifting mechanism and raised the lever or cable to shift the hooks.

Less complex proposals suggested manipulating the hanger beam until the load engaging hooks were touched down. In practicing these proposals one hook was shifted toward or away from the other hook by a series of operations of the hanger beam during which the beam was lowered and then shifted laterally. The other hook was then shifted in the same manner. In some proposals of the last mentioned type the hook structure was supported by a cam track formed in the hanger beam so that as the hanger beam was moved with a hook touched down, the hook structure followed the cam track.

While less complex, these latter proposals have not been fully satisfactory. With these less complex proposals the operator, in practice, lowers the hanger beam until one hook is supported by a surface elevated from the floor. If there is slight overtravel as the hanger beam is lowered, the weight of the hanger beam will be supported by the rigid hook structure. When the hanger is so supported the hanger beam cables are relieved of their load and go slack. The cables, when slackened, often become disengaged from the sheaves about which they are trained. Retraining the cables in such circumstances can be extremely time consuming.

In cases where the hanger beam is to be manipulated with the load engaging hooks touched down on a horizontal surface, the operator of the crane is oftentimes unable to determine when the weight of the hanger beam is being supported by the hooks. In many instances the only way that a crane operator can determine that the hanger beam is being supported by a hook is by visually determining that the cables are slack. This procedure is not desirable since any slackening of the cables risks disengaging them from the sheaves. The use of such proposals has therefore required highly skillful crane operators, and resulted in relatively slow shifting of the hooks. Even so, disengaging the cables from their sheaves is common.

While it is apparent that retaining crane cables consumes otherwise usable time, the time required to shift hooks on cranes is important because of the great demand for crane service on the floor of a plant such as a steel mill. Thus quick and reliable hook shifting is necessary for efficient operation throughout the plant.

Typically the hooks are rounded at their lower ends in a plane which is transverse to the trunions. When a hook is shifted this curved surface engages the support in line contact along a line that parallels the trunion axis. This contact causes difficulties because the line of contact is parallel to the direction of shifting along the hanger beam. As a result, the hooks tend to resist tilting. When the hooks do tilt, the contact between the hook and horizontal surface is essentially point contact as the curved edge of the hook engages the horizontal surface. Because of the point contact, the hooks tend to twist about their longitudinal axes and may tilt in a direction transverse to the desired tilt. Such twisting and tilting has necessitated the provision of narrow cam tracks in the hanger beam for receiving a pin or shaft on the hook structure so that skewing of the hook structure is minimized. The provision of narrow cam tracks has further increased the susceptibility of the ca-

bles to become untrained from their sheaves during shifting of the hooks.

SUMMARY OF THE INVENTION

In accordance with the present invention a load supporting structure of the type referred to is provided with a hanger beam which carries spaced hook assemblies each composed of a hook and support structure. The hanger has spaced bearing seats engageable by bearing members which form a part of the hook supports. The hook assemblies are simultaneously shiftable, in a simple and reliable manner, between the spaced bearing seats without need of hook shifting mechanisms. Manipulation of the hanger beam is such that shifting the hook assemblies between alternate bearing seats is reliably accomplished by simultaneously touching the hooks down without slackening the cables. More specifically the hook assemblies are constrained for freely rotating about the lower end of the hooks as the assemblies are shifted between the bearing seats. This is to say that the beam is constructed so that shifting of the hooks occurs without interference between the hook assemblies and portions of the beam during at least a part of the shifting motion of the hook assembly.

In a preferred embodiment cam surfaces are provided on the hanger beam which are constructed and arranged to guide the hook assemblies toward and away from the bearing seats during the initial and terminal portions of shifting. The hook assemblies tip and rotate freely between the cam surfaces during the remainder of the shifting movement. The cam surfaces are spaced apart so that an operator of the crane can visually determine when shifting of the hook support has been accomplished. Thus, shifting the hook support is accomplished without supporting the weight of the hanger beam upon the hook assemblies at any time, insuring that the cables are not disengaged from their sheaves and permitting less assiduous manipulation of the crane.

In the preferred form of the invention a pair of hook assemblies are supported in openings in the hanger beam. Each opening defines spaced bearing seats and cam portions adjacent the bearing seats. A bearing part of the corresponding hook engages a selected one of the spaced bearing seats on the hanger beam for suspending a load from that seat.

If it is desired to shift the hook assemblies between their respective bearing seats, the hanger beam is lowered until the hooks are touched down. The hanger beam continues to be moved vertically downwardly relative to the bearing part of each assembly. The vertical relative movement urges the bearing part of each assembly along a cam surface adjacent the bearing seat. The cam surface guides the bearing part from the seat and after a predetermined amount of downward movement of the hanger beam the hook assembly is tipped. This causes the bearing part of the hook support to "fall" away from the cam surface and into engagement with a second cam surface adjacent the other bearing seat.

Tipping of the hook assemblies is pronounced and an operator of the crane can thus visually determine when the assembly has tipped. The downward movement of the hanger beam is then terminated. Each opening in the beam provides a substantial clearance between the bearing part and any surface of the beam which could

transmit substantial vertical forces during shifting of the hook. Thus immediate stopping of the downward movement of the beam after the hook assemblies shift is not necessary.

5 The hanger beam is then raised and the bearing parts follow their respective second cam surfaces onto the other bearing seat. The bearing part is therefore guided into engagement with the second bearing seat of the hanger beam. Loads can then be suspended from the second mentioned bearing seat.

10 The hooks are constructed so that when touched down, they engage a floor or other support surface along a narrow line of contact. The line contact is transverse to the direction in which the bearing part is shifted relative to the hanger beam. Thus the hook assembly is constrained from tipping about the line of contact of the hook or grab with the support surface.

15 The cam portions of the hanger beam are disposed so that tipping of the hook assembly and attendant transfer of bearing part contact from one cam portion to the other cam occurs at a time when the bearing part is spaced substantially from any surface of the hanger beam capable of transmitting substantial vertical forces. Accordingly, exertion of vertical forces upon the hanger beam by the hook assemblies is avoided and the possibility of disengagement of the cables with the sheaves minimized.

20 30 The hanger beam and bearing parts are interconnected by stabilizer links engaged with the bearing parts and the hanger beam. The connection between the stabilizer links and a bearing part of the hook assembly prevents a relative rotation between the stabilizer links and bearing part. The connection between the stabilizer link and hanger beam affords relative rotation therebetween as well as sliding movement of the stabilizer link relative to the hanger beam. A stabilizer link constructed as described prevents skewing of the bearing part relative to the hanger beam which might otherwise occur yet permits unrestricted tipping of the hook assemblies about the lower end of the hook.

25 35 Where the hanger beam is constructed to support loads exerting a resultant force which is not centered on the span of the hanger beam, the hook assemblies may be shifted between multiple positions for transporting different sized loads. In one embodiment of the invention, in which each hook assembly has only two positions, four different distances between the hooks are selectively available.

40 45 50 A principal object of the present invention is the provision of a new and improved overhead load supporting structure wherein hook assemblies can be simultaneously shifted relative to a hanger beam of the crane quickly and without disengaging cables supporting the hanger beam from their sheaves.

55 60 Other objects and advantages of the present invention are apparent from the following detailed description thereof made with reference to the accompanying drawings which form a part of the specification.

DESCRIPTION OF THE DRAWINGS

FIG. 1 is an elevational view of a load supporting structure embodying the present invention;

FIG. 2 is a sectional view of a portion of the structure of FIG. 1 viewed approximately from the plane of line 2-2 of FIG. 1 and shown on a scale which is larger than the scale of FIG. 1;

FIG. 3 is an enlarged view approximately from the plane of the line 3—3 of FIG. 2;

FIG. 4 is a fragmentary elevational view seen from the plane of the line 4—4 of FIG. 1;

FIG. 5 is an enlarged view as seen from the plane of the line 5—5 of FIG. 4;

FIG. 6 is an elevational view of a part of the structure of FIG. 1 in one operative condition; and

FIGS. 7 and 8 are fragmentary views of modified load supporting structures embodying the invention.

DESCRIPTION OF THE PREFERRED EMBODIMENT

A crane structure 10 embodying the present invention is illustrated in FIG. 1. The crane structure 10 includes a trolley T, hanger beam B and a hoist mechanism H. The trolley T is movable along tracks 11, 12 which are supported at elevated locations relative to a floor 13, or other horizontal surface. The trolley T is provided with wheels 14, only a pair of which are illustrated, which permit the trolley T to be propelled along the tracks 11, 12 by a suitable prime mover (not shown). The tracks 11, 12 are also movable as a unit transversely of their extent and since the structure for moving the tracks may be of any one of a number of conventional constructions it is not illustrated or described. The illustrated embodiment of the overhead construction is merely illustrative and may in fact merely comprise a trolley on fixed tracks since the invention can be practiced without lateral movement of the hanger beam B.

The hanger beam B is suspended from the trolley T by cables 15, 16. The cables 15, 16 are disposed about sheaves 20, 21 connected to the beam B and extend between the sheaves 20, 21 and the hoist H. The hoist H is operative to effect vertical movement of the beam B relative to the trolley T with the cables 15, 16 being trained around the sheaves to provide a mechanical advantage in moving the beam B.

The beam B is comprised of three plates 22-24 (FIG. 2) which are rigidly fixed together in spaced relation to define an integral beam assembly. The beam assembly includes a center span 25 and load supporting ends 26, 27 which support load supporting hook assemblies 30, 31 respectively.

The hook assemblies 30, 31 are identical in construction and accordingly only the assembly 31 is described in detail in reference to its construction and mode of operation with respect to the beam B. The hook assembly 31 includes a hook support structure 33 which is engaged with the end 27 of the beam B and a load engaging grab or hook 34. The hook support 33 includes a clevice pin 35 which supports the hook 34. The hook 34 is pivoted in a plane transverse to the beam B about the clevice pin 35. The hook 34 is constructed of steel laminations each shaped to define a load engaging portion 36 engageable with ladle trunnions as well as other loads.

The hook support 33 includes a bearing part in the form of a pin 40 which suspends the support from the beam B. The pin 40 is engaged with a suitable bearing seat on the beam B, which seat is described in greater detail presently. The hook support 33 additionally includes bushings 41, 42 surrounding the bearing pin 40. The bushings 41, 42 are integrally connected to side walls 44 of the support 33. The bushings are also connected to vertically extending walls 45, and a horizon-

5 tally disposed wall 46. The walls 45, 46 also form portions of the support and they extend transversely between the side walls 44 at spaced locations in the support. The walls 45 support the bushings 41, 42 at their upper ends and are connected to the wall 46 at their lower ends.

The side walls 44 of the support 33 extend downwardly from the wall members 45 and are apertured to receive and support the clevice pin 35. Journals 50 are disposed around the pin 35 and between the walls 44 and an eye 51 of the hook 34.

15 The bearing pin 40 is a generally cylindrical, shaft-like member which extends through aligned generally triangular openings, 55b—57b in the plates 22-24, respectively at the end 27. The openings 55b—57b are identical in configuration and function and accordingly, only the opening 57b in the plate 24 is described. The opening 57b includes an arcuately curved base surface 60 and converging side surfaces 61, 62 extending from the base 60. The base surface 60 is transversely curved adjacent its junctures with the sides 61, 62 to define bearing seats 63, 64 which are engaged selectively and one at a time, with the bearing pin 40. Thus, the hook assembly 31 may be suspended from the beam B by engagement of the bearing pin 40 with a selected one of the seats 63, 64. The side surfaces 61, 62 extend from the seats 63, 64 to an apex 65 of the opening 57b formed by a gently curving juncture between the sides 61, 62.

20 In accordance with the present invention the hook assembly 31 is shiftable between a position wherein the bearing pin 40 engages the seat 64 and a position wherein the pin 40 engages the seat 63. The change in position of the assembly 31 relative to the beam B is illustrated in broken lines in FIG. 1.

OPERATION

25 To effect a transfer of the bearing pin 40 from the seat 64 to the seat 63, the beam B is lowered relative to the trolley T by operation of the hoist H until the hook 36 touches the floor 13. Further lowering of the beam B results in the bearing pin 40 moving upwardly with respect to the beam B so that the bearing pin 40 is guided along the side of the openings 55b—57b. The sides 61, 62 of the openings 55b—57b thus define a cam portion of the beam which is defined by three spaced cam surfaces on the plates 22, 23, 24. The cam portion guides the bearing pin 40 as the beam B moves downwardly relative to the member 31. The cam portion thus constrains the bearing pin 40 for movement in a longitudinal direction with respect to the descending beam.

30 When the beam B has been lowered to a position at which the bearing pin 40 is approximately at the location 70 on the cam surface 62, the bearing pin 40 has been guided laterally, relative to the hook portion 36, a sufficient distance to unbalance the assembly 31. The force of gravity tips the assembly 31 out of engagement with the cam surface 62 and the assembly 31 "falls" or is tipped so that the bearing pin 40 moves from the cam surface 62 across the opening 57 and into engagement with the cam surface 61.

35 During the tipping action described, the assembly 31 rotates freely about the line of engagement between the hook portion 36 and floor 13 so that the bearing pin 40 strikes the cam surface 61 at a location 71 having a slightly lower elevation than the location 70 on the cam

surface 62. The rotation of the assembly 31 occurs through a large enough angle so that an operator of the crane can visually determine when the bearing pin 40 is in engagement with the cam surface 61. Upon visually determining that the assembly 31 has shifted, the crane operator actuates the hoist H to elevate the beam B relative to the floor 13. The cam surface 61 moves upwardly relative to the bearing pin 40 and the surfaces 60, 61 coact to guide the bearing pin 40 into engagement with the seat 63. Continued upward movement of the beam B results in rotation of the hook assembly 31 about the bearing pin 40 until the assembly depends vertically from the seat 63 in its vertical broken line position (see FIG. 1).

It should be apparent that the apex 65 of the opening 57b is spaced a relatively substantial distance from the bearing pin 40 at all times during shifting of the bearing pin 40 relative to the beam B. Accordingly, support of the beam B by the assembly 31 during downward movement of the beam B is avoided. The bearing pin 40 does not engage a horizontal surface of the opening 57b at any time during movement from the bearing surface 64 to the bearing surface 63.

The gently curved apex 65 merges smoothly into the cam surfaces 61, 62 but does not cam the bearing 40 relative to the opening 57b and in fact is not engaged by the pin 40 at all. The reason for the gently curving configuration of the apex 65 is to minimize stress concentrations in the plates 22-24 of the beam B under load. The base surface 60 of the opening 57 is recurved to provide generally cylindrical bearing seats at its junctures with the sides 61, 62. In the preferred operation as depicted in FIG. 3 the base surface 60 does not participate in camming the pin 40 between its positions and thus pin wear is avoided. The gently curving base surface 60 is so configured to reduce stress concentrations around the opening 57b but may assist in camming the pin 40 against the seat 63 if the beam B is raised very rapidly.

The foregoing description of the operation of the crane 10 in shifting the assembly 31 also applies to shifting the bearing pin 40 of the assembly 30 in the openings 55a-57a at the end 25 of the beam B. As illustrated in FIG. 1, while the assembly 31 is being shifted toward the assembly 30, in the manner described, the assembly 30 is simultaneously shifted toward the assembly 31 in a mirror image manner. Accordingly, a detailed description of shifting the assembly 30 would be superfluous and is omitted.

Similarly, the operation for shifting the hook assemblies 30, 31 from their vertical phantom positions of FIG. 1 to their solid line positions is identical except that the assemblies tip in opposite directions.

THE HOOK CONSTRUCTION

The hook portion 36 is constructed to provide a relatively narrow substantial line contact with the floor 13 in a direction transverse to the beam B. As illustrated in FIGS. 4 and 5 the hook 34 is formed by a plurality of laminations of sheet steel with the laminations in the central portion of the hooks extending into engagement with the floor 13. The outer laminations terminate short of the floor 13 when the hook is touched down. Thus when a hook is touched down, contact with the floor is established along a line transverse to the beam B, inhibiting tipping of any part of the assembly 31 transversely of the beam but readily permitting tipping

of the assembly 31 about the line of contact with the floor. The line contact described additionally functions to inhibit the tendency of the hook assembly to twist about its vertical axis even during tipping.

THE STABILIZING MECHANISM

The assembly 31 is susceptible to pivoting or twisting about the longitudinal axis of the member even though line contact is established between the hook and floor as noted. Such pivoting tends to occur when the bearing pin 40 is being shifted and particularly if the hanger beam is swinging. Twisting of the assembly 31 could result in skewing of the bearing pin 40 relative to the cams and seats of the openings 55-57, resulting delays in shifting the hooks.

To avoid this problem the crane structure of the present invention is equipped with stabilizing mechanisms for preventing skewing of the bearing pins 40 relative to the cam surfaces and bearing seats defined by the openings 55-57. In the preferred embodiment each stabilizing structure includes a link 80 connected between the bearing pin 40 of each assembly 30, 31 and the plates 22-24 of the beam B. The stabilizers are identical in construction and accordingly only the stabilizers associated with the plates 22, 24 and the assembly 31 are described in detail. The links 80 each include a square opening 81 adjacent one end and an elongated slot 82 at the opposite end. Each slot 82 receives a guide pin 83 fixed to the adjacent one of the plates 22, 24. Coaction of each guide pin and its associated slot permits rotational as well as translational movement of the link 80 relative to the beam B.

The bearing pin 40 includes reduced end portions 84 at each of its ends which are square in cross-section and are snugly received in the openings 81 to fix the bearing pin 40 and links 80 against rotation relative to each other. The ends 84 of the bearing pins 40 are provided with threaded holes. A plate-like retainer member 85 is secured to the ends 84 by screws 86 which extend through the retainer 85 and into the holes (FIG. 2).

The links 80 are connected at the ends of each bearing pin 40 (FIG. 2) in the manner described, so that as the bearing pin 40 is moved relative to the openings 55b-57b the links 80 slide and rotate with respect to the pins 83. Should the bearing pin 40 tend to skew relative to the cams, i.e. when the bearing pin 40 tends to assume a position in which its axis is not transverse to the beam B, the ends 84 of the pin 40 exert forces on the links 80 tending to rotate the link about the longitudinal axis of the bearing pins. Due to the pin and slot connection between the links 80 and the beam B, any tendency for rotation of the links 80 about points other than the axis of the guide pins 83 is strongly resisted by the engagement of the sides of the slots 82 with the guide pins. Thus the links 80 must rotate in unison and accordingly lock the pins against skewing.

It will be appreciated from the foregoing description that the rotational and translational pin movement permitted by the stabilizers is such that the hook assemblies can rotate freely about the lower end of the hook during tipping. Furthermore the links 80 freely permit such tipping regardless of the vertical length of the hook assemblies.

THE HOOK ASSEMBLY POSITIONS

From the foregoing description it is apparent that the openings 55-57 in ends of the beam B permit simulta-

neous shifting of the hook assemblies 31 between a "wide" position and a "narrow" position. The hooks thus engage loads having diametrical extents which differ by an amount equal to the sum of the distances between the seats 63, 64 of the openings 55-57 at each end of the beam B.

Where the crane structure 10 is designed to permit eccentric loading of the beam B (i.e. where the beam B supports a load having a resultant acting on a location of the beam B which is not equidistant between the sheaves 20, 21), an "intermediate" hook position can be provided by shifting only one of the assemblies 30, or 31. The "intermediate" position provides a distance between the hooks which is intermediate the "wide" and "narrow" positions referred to by an amount equal to the distance D between the seats 63, 64 of the openings 55-57 at one end of the beam (see FIG. 7).

As seen in FIG. 6, positioning of the members 30, 31 at the intermediate position is accomplished by providing a suitable elevated surface 13a beneath a selected assembly, the assembly 31 as shown, and lowering the beam B until the hook 34 touches down on the surface 13a. The beam B continues to move downwardly until the assembly 31 is shifted from the seat 64 to the cam 61. Then the beam B is again raised so that the assembly 31 is suspended from the seat 63, as illustrated in broken lines in FIG. 6. It is to be noted that the surface 13a is elevated a sufficient distance above the floor 13 to insure that the hook of the assembly 30 does not touch down on the floor during shifting of the assembly 31. Thus the assembly 30 is maintained in its FIG. 6 position during shifting of the assembly. It is also apparent that the assembly 30 can be individually shifted in the manner described utilizing the elevated surface 13a.

FIG. 7 is illustrative of the possible positions at which the assemblies 30, 31 may be supported relative to the beam B. FIG. 7 additionally illustrates a modified construction of the openings 55-57 in the beam B wherein the apexes 65 of the openings are defined by slot-like recesses 65a. The upper ends of the recess 65a are defined by a generally circularly curved surface so that stress concentrations around the openings are minimized.

The recesses 65a are constructed to provide substantial clearance between the apexes of the openings 55-57 and the path followed by the bearing pins 40 during shifting between the seats 63, 64. This construction permits increased latitude in operation of the hoist H, during shifting of the assemblies 30, 31 as compared with the construction described in reference to FIGS. 1-6.

The positions at which the assemblies 30, 31 can be supported on the beam B are illustrated in FIG. 7 including the "wide," "narrow," and two "intermediate" positions. The intermediate positions space the hooks equal distances apart due to the openings 55-57 at the ends of the beam being of the same size and shape. Although the hook spacing is the same, the intermediate positions provide for the resultant force of the load supported by the beam to be exerted at a location on a desired side of the center of the beam B.

FIG. 8 illustrates a modified beam B' having openings 90, 91 which are of different configurations to permit the assemblies 30, 31 to be supported by the beam B' at positions which provide four different hook spacings.

The opening 90 is a generally triangular opening having a curvilinear base 94 and sides 95, 96 which are joined by a smoothly curved apex 97. The junctures between the base 94 and sides 95, 96 are circularly curved to define seats 100, 101 for the bearing pin 40. The seats 100, 101 have a center line distance D+X therebetween. The sides 95, 96 of the opening 90 converge proceeding upwardly with each of the sides defining an angle alpha, with respect to horizontal.

10 The opening 91 includes a base surface 104 and sides 105, 106 which are interconnected at the apex 107 of the opening 91 by a smoothly curving surface. The junctures of the sides 105, 106, respectively and the base 104 define circularly curved seats 110, 111 having a center line distance D-X therebetween. It is apparent that the triangular openings 90, 91 are not similar and the sides 105, 106 of the opening 91 converge proceeding upwardly at an angle beta, with respect to horizontal and which angle is substantially larger than the angle alpha.

20 When the bearing pin 40 of the assembly 30 is disposed on the seat 100 of the opening 90 the bearing pin 40 of the assembly 31 can be disposed on the seat 111 of the opening 91 to provide a "wide" or maximum spacing between the hooks. Shifting the bearing pin 40 of the assembly 31 from the seat 111 to the seat 110 of the opening 91 provides a first intermediate distance between the hooks of the assemblies 30, 31 differing from the "wide" or maximum hook spacing by the distance D-X. This intermediate position is termed the "intermediate-wide" position.

25 When the bearing pin 40 of the assemblies 30 is disposed on the seat 101 and the bearing 40 of the assembly 31 as disposed on the seat 111 a second intermediate spacing between the hooks of the assembly 30, 31 is provided which differs from the maximum spacing by the distance D+X. The second intermediate position is termed the "intermediate-narrow" position.

30 Shifting of the bearing pin 40 of the load supporting assembly 31 to the bearing surface 110 provides a "narrow" or minimum hook spacing between the hooks of the assemblies 30, 31.

35 Thus it can be seen that four separate positions of the assemblies 30, 31 on the beam B' can be provided by shifting the assemblies 30, 31 between the locations referred to in reference to FIG. 8. It should be noted that the shifting referred to can be accomplished by utilization of an elevated surface such as the surface 13a referred to in conjunction with FIG. 6.

40 While a single embodiment of the present invention has been illustrated and described herein and in considerable detail the present invention is not to be considered to be limited to the precise construction shown. It is my intention to cover hereby all adaptations modifications and uses of the present invention which come within the scope of the appended claims.

I claim:

1. A load supporting device comprising:
- a. a movable load supporting structure;
- b. a beam suspended from said load supporting structure by flexible supporting members;
- c. hoist means associated with said supporting members for changing the elevation of said beam;
- d. a load engaging assembly suspended from said beam, said assembly including a bearing part engageable with said beam and load engaging part remote from said bearing part;

- e. said beam including a pair of spaced bearing seats, a bearing part of said assembly being selectively engageable with one of the bearing seats of the associated pair of seats;
- f. said beam also including cam means associated with said bearing seats for guiding movement of said bearing part between said bearing seats;
- g. said bearing seats and cam means defined by an opening in said beam member through which said bearing part extends;
- h. a first cam portion of said cam means being effective to guide said bearing part from one of said seats toward said other seat in response to downward movement of said beam relative to said bearing part, said first cam portion guiding said bearing part to a position at which said assembly is unbalanced and exerting a tipping force on said assembly; and,
- i. guiding means for constraining said load engaging assembly for tipping movement out of engagement with said first mentioned cam portion and toward said second bearing seat about a tipping axis which extends transversely of said beam;
- j. said guiding means comprising linkage means connected between said bearing part and said beam member for preventing skewing of said bearing part relative to said opening.

2. A crane as defined in claim 1 including a second load engaging assembly suspended from said beam by a bearing part and wherein said beam defines spaced pairs of said bearing seats, seats of each pair individually engageable with said bearing part of each of said assemblies.

3. A crane as defined in claim 1 wherein cam means includes a second cam portion, said first and second cam portions extending upwardly from said bearing seats and converging proceeding away from said bearing seats, and wherein the location on said first cam portion at which said bearing part of said load engaging members tips out of engagement with said first cam portion is spaced substantially away from a location on said second cam portion where said bearing part engages after tipping of said assembly.

4. A crane as defined in claim 3 wherein converging ends of said first and second cam portions are interconnected by a smoothly curving connecting portion of said opening in said beam member, said connecting portion merging with said cam portions at a location spaced vertically above said locations on said cam portions whereby said bearing part does not contact said connecting portion during shifting between said bearing seats.

5. A crane as defined in claim 1 wherein said linkage means includes a link member connected for rotation with respect to said beam member and fixed against rotation with respect to said bearing part.

6. A crane as defined in claim 5 wherein said connection of said link member to said beam member is a pin and slot connection.

7. A crane as defined in claim 5 and further including a second link member connected for rotation with respect to said beam member and fixed against rotation with respect to said bearing part, said first and second link members connected at opposite ends of said bearing part.

8. A crane as defined in claim 1 wherein said opening in said beam member is generally triangular and said

cam means further includes a second cam portion, said cam portions formed by respective sides of said generally triangular opening and said bearing seats defined by the junctures of a base portion of said triangular opening and the cam portions, respectively, said base portion of said opening located in spaced relation to said bearing part during movement of said bearing part between said seats.

9. A crane as defined in claim 8 wherein said cam portions lie in planes which converge adjacent an apex of said opening and wherein said cam portions are disposed relative to each other so that said bearing part is spaced substantially from said apex at all times during movement between said bearing seats.

10. A crane as defined in claim 9 wherein said apex is defined by a recessed portion above the location at which said cam planes converge, said recessed portion including side walls merging with said cam portions and a smoothly curving wall connecting said side walls.

11. A crane as defined in claim 1 wherein said beam defines spaced apart pairs of said bearing seats, the second pair of said seats cooperable with a bearing part of a second load engaging assembly, said pairs of bearing seats defined by generally triangular openings in said beam and wherein the distance between seats of one pair is greater than the distance between seats of said other pair of seats whereby said bearing parts are engageable with individual ones of said seats to provide four different spacings between said load engaging assemblies.

12. An overhead load supporting structure comprising:

- a. a hanger beam;
- b. a flexible support suspending said beam;
- c. a hoist for effecting vertical movement of said beam;
- d. a load engaging hook assembly on said beam;
- e. said beam including spaced bearing surfaces from which the hook assembly is suspended selectively and one at a time;
- f. said hook assembly comprising a bearing part shiftable between said bearing surfaces and a hook member;
- g. said beam further including structure for exerting a tipping force on said hook assembly for tipping said bearing part toward a bearing surface when said beam is lowered relative to said hook assembly; and,
- h. guiding means for constraining tipping movement of said hook assembly about an axis of rotation transverse to the beam and near the base of said hook assembly as said bearing part is shifting, said guiding means comprising a base of said hook member which engages a horizontal surface along a line of contact defining said axis of rotation.

13. A structure as defined in claim 12 wherein said hook member is defined by a plurality of vertically disposed laminations, laminations along sides of said hook member terminating short of said base.

14. A load supporting structure as defined in claim 12 wherein said guiding means further includes a linkage having a member connected to said hanger beam for sliding and rotational motion and nonrotatably connected to said bearing part, said linkage preventing skewing of said bearing part relative to said hanger beam.

15. A load engaging assembly for connection to a hanger beam comprising:

- a. a shank adapted to be suspended from said beam in a vertical orientation;
- b. a load engaging hook-like portion; and,
- c. a base of said hook-like portion constructed for touching down on a horizontal surface at least at locations spaced apart along a line extending generally transversely of said hanger beam;
- d. said base defining a generally planar surface engageable with the horizontal surface along said line when the assembly is touched down to prevent said hook from tipping about an axis parallel to said hanger beam, said line of contact defining an axis about which said load engaging assembly is rotatable.

16. A load supporting device comprising:

- a. a movable load supporting structure;
- b. a beam suspended from said load supporting structure by flexible supporting members;
- c. hoist means associated with said supporting members for changing the elevation of said beam;
- d. a load engaging assembly suspended from said beam, said assembly including a bearing part engageable with said beam and load engaging hook-like member remote from said bearing part;
- e. said beam including a pair of spaced bearing seats, a bearing part of said assembly being selectively engageable with one of the bearing seats of the associated pair of seats;
- f. said beam also including cam means associated with said bearing seats for guiding movement of said bearing part between said bearing seats;
- g. a first cam portion of said cam means being effective to guide said bearing part from one of said seats toward said other seat in response to downward movement of said beam relative to said bear-

ing part, said first cam portion guiding said bearing part to a position at which said assembly is unbalanced and exerting a tipping force on said assembly; and,

- h. guiding means for constraining said load engaging assembly for tipping movement out of engagement with said first mentioned cam portion and toward said second bearing seat about a tipping axis which extends transversely of said beam;
- i. said guiding means comprising a downward facing surface of said hook-like member engageable with a horizontal surface along a line of contact during downward movement of said beam relative to said bearing part, said line of contact extending transversely of said beam and defining said tipping axis.

17. A load engaging assembly for connection to a hanger beam comprising:

- a. a shank adapted to be suspended from said beam in a vertical orientation;
- b. a load engaging hook-like portion; and,
- c. a base of said hook-like portion constructed for touching down on a horizontal surface at least at locations spaced apart along a line extending generally transversely of said hanger beam;
- d. said base and horizontal surface engaging to prevent said hook from tipping about an axis parallel to said hanger beam;
- e. said hook-like portion defined by a plurality of vertically extending laminations, laminations along sides of said hook-like portion terminating short of said base whereby the width of the locations on which said base touches down is substantially less than the width of said hook-like portion between said sides.
